DETACHABLE MOUNTING FOR WEFT DETECTORS

Richard G. Turner, Worcester, Mass., assignor to Crompton & Knowles Loom Works, Worcester, Mass., a corporation of Massachusetts

Application April 3, 1941, Serial No. 386,612

7 Claims. (Cl. 139—269)

This invention relates to weft detectors for looms and it is the general object of the invention to provide a mounting for the detector from which the latter may be readily detached to permit repairs to the detector tip.

In certain types of weft detectors, particularly those which close an electric circuit by means of a metallic ferrule on the exhausted bobbin, it is desirable to be able to remove any burrs or pits which may occur in the feeler tip due to arc-ing. Occasionally the breaking of the circuit when the lay moves rearwardly results in burning which leaves a black deposit on the feeler tip that is likely to mar the weft on subsequent detecting operations.

In order that the detector may be quickly detached from its mounting so that the tip may be refinished it is an important object of my present invention to provide a support having spring clip means which will embrace a part of a detector to hold it in operative position but which will yield readily to permit removal of the detector.

Electrical detectors operate in connection with an electric circuit in the loom including a solenoid or other electromagnetic device which actuates the replenishing or loom stopping mechanism, and it is a further object of my present invention to provide a form of electric contact between the oppositely charged detector prongs and the circuit which may be readily broken and reestablished when the detector is removed and subsequently replaced. As shown herein-after the circuit may have terminals in the form of prongs stationary on the detector support to receive electrodes projecting from the detector, or may comprise friction socket heads which fit directly on to the wire prongs of the detector. The detector is preferably so constructed as to receive stationary pins which extend in a direction transverse of the force exerted on the prongs at the time of a weft detecting operation. In the practice of my invention the attendant will be provided with a spare detector in proper condition which can be used as a replacement for any detector which must be removed from its mounting for repair.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a plan view of a weft detector and a portion of a shuttle and shuttle box showing the preferred form of my improved mounting for the detector,

Fig. 2 is a side elevation taken in the direction of arrow 2, Fig. 1,

Fig. 3 is a vertical transverse section taken on line 3—3 of Fig. 1,

Fig. 4 is a front elevation taken in the direction of arrow 4, Fig. 2,

Fig. 5 is a detailed plan view of the forward end of a detector similar to that shown in Fig. 1, but with a modified form of detachable electric contact mounted directly on the detector prongs, and

Fig. 6 indicates diagrammatically how the detector tips may be reconditioned.

Referring to Fig. 1, I have indicated the loom lay L and a shuttle box B on it in which is located a shuttle carrying a bobbin 10 carrying a wound mass of weft W. The barrel of the bobbin is provided with a metallic ferrule 11 ordinarily covered by the weft but which becomes uncovered as weft exhaustion approaches.

A stand 15 for supporting the weft detector designated generally at D may either be fixed with respect to the loom frame or mounted for forward motion relatively thereto on replenishing beats of the loom. The detector may be of the type shown in prior Patent No. 1,924,197 and may have a body 20 of insulating material, such as a phenol condensation product, and is provided with a pair of parallel bores 21 and 22 to receive the detector prongs 23 and 24, respectively. Each prong may be provided with an enlarged detector tip 25 of a general form shown in Patent 2,045,960, although it is not necessary to employ the particular metals mentioned in the last named patent, and light compression springs 26 surrounding the detector prongs push rearwardly on collets fixed on the prongs to hold them yieldingly in rear position.

The body 20 preferably has a widened forward end 30 through which extend a pair of vertical holes 31 and the rear end 32 of the de-

tector body may be thinner than the forward end and also of less width as indicated in Figs. 1 and 2. The enlarged forward end of the detector guide has fixed thereto a pair of spaced contacts 35, each having a shank threaded into

one of the bores 21 and 22. The wires prongs 23 and 24 extend forwardly through the contacts 35 to have sliding engagement with their interiors when the lay moves the shuttle forwardly for a detecting operation. Each of the detector contacts may be formed with a forwardly projecting substantially cylindrical lug 36 in the preferred form of the invention. The support 15 has slots 38 extending backwardly and forwardly therein to permit adjustment of the detector toward and from the shuttle by securing means to be described.

The matter thus far described, except as indicated herein, may be substantially the same as that shown for instance in Patent No. 1,924,197 and except for the contact lugs 36 may be

constructed according to established practice. In carrying my present invention into effect I secure a base plate to the support 15 under the detector and provide the plate with means for holding the detector in operative position by connections which permit a ready detachment of the detector from the support. Accordingly, in the preferred form of the invention I use a plate 40 of any approved insulating material and provide the same with a pair of studs 41 which extend upwardly from the top surface of the plate 40. Each stud may be provided with a shoulder 42 which fits into a counterbore 43 sunk into the upper surface of the plate 40. The lower end of each stud 41 extends through the slots 38 in support 15 and is held to the latter by a nut 44 threaded on the lower end of the stud. By means of shoulders 42 and nuts 44 the plate 40 is held securely to the support 15, and the studs are so spaced by the plate that they project upwardly through the vertical holes 31 in the detector body. The upper ends of the studs are substantially the same diameter as the holes 31, thus permitting the detector to be slid upwardly off the studs.

The rear part of the plate 40 carries a spring clip 50 having a lower horizontal web 51 which is riveted as at 52 to the plate 40, and lateral upwardly extending spring arms 53 each provided with a hook 54 are bent up from the web 51 and integral therewith. When in normal position the hooks 54 extend over the top of the rear narrow end 32 of the detector body and hold the latter in position on the plate 40 with the web 51 extending under the thinner part 32. The web 51 may be of such thickness as to engage the bottom of end 32 and afford solid support for it, as indicated in Fig. 3.

The forward end of plate 40 is provided with a pair of electric contact spring clips 55 each having a base 56 through which extends a contact screw 57 to hold the clip on the base and afford electric contact with a wire 58 forming part of a loom controlling circuit not shown. Each clip is provided with a pair of resilient upwardly extending spaced separable arms 59 to receive one of the lugs 36. The arms 59 establish a close frictional contact with the lugs 36 and the wires 58 are permanently connected to the spring contacts 55.

In the operation of the preferred form of the invention the tips 25 will engage the bobbin on each detecting beat of the loom and be moved forwardly in the body 20 against the resistance of springs 26. When the tips engage the ferrule 11 they are electrically connected and the wire prongs 23 and 24, because of their sliding engagement with contacts 35, electrically connect wires 58 to close the loom controlling circuit.

Should the yarn engaging portions of the detector tips become pitted or blackened the resilient hooks 54 may be spread apart and the detector moved upwardly, thereby moving the lugs 36 out of the spring clips 55 and also raising the detector body to a point above the tops of the supporting studs 41. The detector may then be replaced by a similar detector in proper condition merely by inserting a new detector downwardly along the studs 41 to cause the arms 54 and 59 to spread apart and then snap back to normal position to hold those parts of the detector positioned for engagement with them.

The detector then may be taken to a polishing

or burnishing device, which as indicated in Fig. 6, may comprise a motor M, having a shaft 60 to which is attached a polishing head 61 of leather or other suitable material and having a concave socket 62 proportioned to receive the rear ends of the detector tips. Each of the latter can thus be reconditioned and the detector kept by the attendant to be used as a replacement for the next detector which must be reconditioned.

In the modified form of the invention shown in Fig. 5 the contact screws 65 will replace those used in the preferred form and the electric detector prongs 66 and 67 will project forwardly far enough to be detachably connected to spring socket heads 68 attached to the ends of wires 69 which correspond to wires 58 of the preferred form. Electric current can therefore pass from the detector prongs 66 and 67 to the wires 69 without passing through a sliding contact. When the detector is to be removed the detachable spring contacts 68 are slid forwardly from the detector prongs. In other respects the modified form of detector is similar to the preferred form.

While I have described my invention with particular reference to an electrical weft detector certain features of my invention such for instance as the stud 41 and spring arms 54, are adaptable for holding the weft detector which is not necessarily of the electrical type. While it is convenient to adapt my invention to already existing structures by the use of the insulated plate, I do not wish thus to be limited, inasmuch as it is sufficient if the spring clips are rigid with respect to the support 15 and the electrical clips 55, when used, are insulated from the support. In this connection it is to be noted that certain types of weft detectors other than electrical may require conditioning of their tips in order to maintain efficient operation.

From the foregoing it will be seen that I have provided a simple form of mounting for a detector which permits the latter to be detached readily from its support so that the damaged weft engaging tip may be reconditioned. It will be seen that the insulating plate 40 is provided with a spring clip to embrace a portion of the detector body and hold the latter to the plate 40, which in turn is held to the support 15 by means of the studs 41. The latter extend in a direction transverse of the direction in which the detector prongs slide and thus withstand any tendency to disturb the detector in its setting during repeated detecting operations. It will further be seen that in the preferred form the external circuit is connected to the detector prongs by means of the clips 55 which are permanently connected to the plate 40 and extend upwardly so that upward motion of the detector necessary to move it off the studs 41 will at the same time disconnect the lugs 36 from the prongs 55. In the modified form the spring clip 50 and the studs 41 will be substantially the same as in the preferred form, but the external circuit is connected to the detector by means of spring clip sockets which can be slid off the forward ends of the prongs 66 and 67 prior to removal of the detector from the loom.

Having thus described my invention it will be seen that changes and modifications may be made therein by those skilled in the art without departing from the spirit and scope of the invention and I do not wish to be limited to the details herein disclosed, but what I claim is:

1. In a mounting for a weft detector having a

body provided with an aperture extending therethrough, a support for the detector, a plate between the detector and the support, a guide stud on the plate extending through the aperture, means to hold the stud on the support, spring clip means on the plate engaging opposite sides of the detector to hold the latter to the plate and movable to detector releasing position by a motion transverse of the direction in which said aperture extends, and a shoulder on the stud between the detector and plate and held against vertical motion relatively to the plate and detector when the latter is held to the plate by said spring clip means, whereby the stud, detector and plate constitute a unit held together by said spring clip means.

2. In a mounting for a weft detector having a body provided with an aperture extending vertically therethrough, a support for the detector, a plate between the support and the detector, a guide stud projecting upwardly from the plate through the aperture, spring clip means on the plate having resilient arms movable normally toward holding position with respect to said body of the detector in directions transverse of the directions in which said aperture extends and yieldable in directions away from each other to release the detector, whereby the latter may be raised to a position above the guide means on the plate, and a shoulder on the stud between the detector and plate and held against vertical motion relatively to the plate and detector when the latter is held to the plate by said spring clip means, whereby the stud, detector and plate constitute a unit held together by said spring clip means.

3. In a mounting for a weft detector having a body provided with apertures extending vertically therethrough, a support for the detector, a plate between the support and the detector, studs the upper parts of which constitute guide pins extending upwardly from the plate through said apertures to hold the detector against displacement in a horizontal direction relatively to the plate, spring clip means having a body extending under the detector and secured to the plate and having resilient side arms extending upwardly and normally over the upper surface of the detector to prevent upward motion of the detector relatively to the plate, a shoulder formed on each stud located between the detector and plate to prevent vertical motion of the stud relatively to the detector and plate when said detector is held to the plate by said spring clip means, and means on the lower parts of the studs below their respective shoulders to fasten the plate to said support, said side arms being yieldable in directions away from the body of the detector to release the latter and permit the same to be moved upwardly to a position above the guide pins.

4. In a mounting for an electrical weft detector having a body with vertically extending apertures therethrough and in which are mounted horizontally slidable detector elements the rear ends of which project behind the body of the detector and the forward ends of which slide through contact elements, a support for the detector, a plate formed of insulating material located between the support and the body of the detector, spring clip means secured to the plate and including upwardly extending arms to over-

hang portions of the detector and hold the latter normally against upward motion relatively to the plate, guide pins projecting upwardly from said plate through the apertures to prevent horizontal motion of the detector relatively to the support, resilient contact members extending upwardly from the plate and normally in contacting relationship with respect to said contact elements, the resilient arms being movable out of holding relation with respect to the body of the detector and the latter being movable upwardly along the guide pins to move the contact elements out of engagement with the contact members, and a shoulder on each pin between the detector body and said plate held against upward motion relatively to the detector and plate by said spring clip means when the latter overhangs portions of the detector.

5. A weft detecting unit for a loom having a weft surface to be detected and provided with a support to which the unit is to be secured, said unit comprising a weft detector having parts to engage the surface to be detected, a plate under the detector, a stud passing through the detector and plate and having a shoulder located between the detector and the plate, the lower part of said stud being of sufficient length to be attached to the support, and spring clip means on the plate to engage a portion of the detector and hold the latter to the plate, said spring clip means holding the detector, the plate and the stud together as an organized unit when the stud is being secured to said support.

6. A weft detecting unit for a loom having a weft surface to be detected and provided with a support to which the unit is to be secured, said unit comprising a detector having insulated electrical feeler elements for engagement with said surface, a plate formed of insulating material under the detector, insulated contacts on the plate for said elements, a stud passing through said detector and plate and having a shoulder located between the detector and the plate, a portion of said stud being formed for attachment to the support, and spring clip means on said plate removably holding the detector to said plate, said spring clip means holding the detector, the plate and the stud together as an organized unit with said elements in engagement with their respective contacts when said unit is being attached to said support.

7. In a weft detecting unit for a loom having a surface to be detected and provided with a support for the unit having formed therein a slot extending in a direction toward and from said surface to be detected, said unit comprising a weft detector having portions to engage said surface, a plate under said detector, a stud passing through said detector and plate and formed to have a portion thereof extending through said slot for holding relation with respect to said support, spring clip means on the plate to hold the detector to said plate and movable to positions to release said detector from the plate, and a shoulder formed on the stud and located between the plate and the detector, said spring clip means holding the detector and plate and stud together as an organized unit to permit movement of said unit toward and from the surface to be detected when the stud is adjusted along said slot.
